Adam Brooks 441

The substance referred to in these Letters Patent now forming part of the same containing a description in the words of the said Adam Brooks himself of his "Improvement in the machine for winding silk from the cocoon."

To all to whom these presents shall come, be it known that of Adam Brooks of Scituate in the County of Plymouth, and State of Massachusetts have invented and made ready a useful improvement in the machine for spinning silk, for which machine I have obtained Letters Patent on the twenty ninth day of June

A. D. 1833. For such parts of which as I have made use of in my last reference to be had to this original draft, and to be stale in the patent office at Washington - and the following is a full and exact description of the improvement on that machine by me. A represents the main rollers that must be covered with high wire or brads plated, or some metal, as iron will rust and break the silk if used to spin the silk out from the cocoon, on the end of said roller is a screw, operating with a toothed wheel upon the end of shaft B, upon the lower end of which is a screw which carries another toothed wheel C, which wheel is on the shaft B, and carries the heart pinion D, D, which in revolving carries shaft E upon the ends of which are feelings that swing upon the beams through which moves the rail marked F, up and down, thereby laying the said screw upon the shaft, when the middle of said F is a screw, operating with which as the rail moves up and down it causes an elliptical motion with which is connected with a vibrating line, in which are guide wires to guide the thread as it is drawn between the rollers at a perpendicular rods from the upper roller, the lower end of which being worked in a frame

to a plate and strip A, the object of which is to hold the two spindles on each side of plowshare, & is confined (and always) upon an axle fastened to the upper rail of the frame. The upper end of said axle receives over the top roller and which roller is affixed to the frame by a bolt to govern same at the ends of the sills, and which operates to stop and start the spindles instantaneously on the operation of rod. It being made about two inches longer and having a rod fixed to it passing across the bands, and be fixed either by being cast, or having fullings forged, so as that the handles "T" or "L" are moved forward and back, it will raise the band onto a loose wheel or freely on the spindle to stop it, and return the band onto the wheel ~~and~~ ^{to} bring it to rest at in motion, again, on the band, and may be fixed to a loose wheel on the spindle that carries the chain by a check which rod will raise the wheel off and release it to regulate the spindle at pleasure. When either of the last described methods are adopted, then the lower part of rod. It should be dispensed with by fastening the handles on rods "L" or "T", the roller can be raised and spindle stopped to perfect the biseau, by either plan above mentioned. K.K.K.K. are small bows in the end of which are two wires to guide the thimble over the head of the spade. V.V. are two bows passing through the upper rail in front, in the end of which are three curled wires which are placed in rectangular form so that in doubling twist it will regularly unite the several parts into a cord, before it is twisted by the spindle below. D. is a third roller over which the three spades and back between the two that and the next. (one) then passed between the two former bows, which is used in doubling sewing silk and twine, and causes a bearing thirty graining thread over. The rod "T" being horizontal.

tally, is perpendicular to the perpendicular axis mentioned I said
 is also used for stopping the threads at pleasure. It is a
 line or east iron plane with partitions with holes through
 them for the water to pass equally from one to the other. C.C.
 are the parts of the plane for the oars while sailing; L.L.
 are the parts of the plane in which to keep the oars, and to collect
 the threads to supply when wanting. C.C. represents the door of
 the furnace which is to heat the water in the plane above
 and in which furnace there is a grate within about four
 inches of the top; and in which furnace can be used wood or
 charcoal. O. is a pulley upon the side of the cylinder which
 is common used out to be about four inches diameter, but
 which may be raised as the taste of the master requires.
 M. is a standing pulley whose power is designed to be applied
 N. is a loose pulley to stop the machinery at pleasure.
 P. is a bolt passing through the upper rail operating through
 a spiral spring to hold the upper rail down. This being
 done by the same or a weight, the rings in bar P
 I do not claim to have invented, but use them by permission
 of the patentee in this engine, but I claim the applica-
 tion of the spindle and rings to spin full immediate-
 ly as it comes from the cascade. I have used them by
 hand they will bear the greatest speed of any now in
 use. The above draft and model are designed to be en-
 larged so as to carry any number of spindles that may
 be wanted and which I have already increased to great
 advantage, and water, steam or any other kind of
 power can be applied to it.
